UNITED STATES PATENT OFFICE.

MINER E. WORDEN, OF SCRANTON, PENNSYLVANIA, ASSIGNOR OF TWO-
THIRDS TO STEPHEN S. SPRUKS, OF SCRANTON, PENNSYLVANIA.

HAME.

No. 797,930.

Specification of Letters Patent.

Patented Aug. 22, 1905.

Application filed December 31, 1904. Serial No. 239,144.

To all whom it may concern:

Be it known that I, MINER E. WORDEN, a citizen of the United States, residing at Scranton, in the county of Lackawanna and State of Pennsylvania, have invented certain new and useful Improvements in Hames; and I do hereby declare the following to be a full, clear, and exact description of the invention, such as will enable others skilled in the art to which it appertains to make and use the same.

This invention relates to certain new and useful improvements in harnesses, and more particularly to hames.

The object of the invention is the production of a simple and comparatively inexpensive hame which is durable in construction and of great utility for the purposes for which it is to be employed.

Another object of the invention is the improvement of the general structure of the hame, said hame being preferably formed of metal.

A further object of the invention is the provision of means formed upon a hame for preventing the fastening means which is employed for securing a trace thereto from chafing or in any way injuring the animal upon which said hame may be carried.

With these and other objects in view the invention consists in certain novel constructions, combinations, and arrangements of parts, as will be hereinafter fully described, illustrated in the accompanying drawings, and more particularly pointed out in the claims hereto appended.

In the drawings, Figure 1 is a front view in elevation of a pair of connected hames. Fig. 2 is a transverse sectional view of a hame, taken on line 2 2, Fig. 1. Fig. 3 is a fragmentary side view of the hame, showing its hook moved at approximately right angles to its normal position. Fig. 4 is a perspective view of a fastening device employed in connecting two hames. Fig. 5 is a fragmentary side view of a hame to which is removably secured a looped member.

Like numerals of reference designate corresponding parts throughout all the figures of the drawings.

While in Fig. 1 of the drawings I have shown a pair of connected hames, it will only be necessary to describe the structure of one, as each of the hames is similar in construc-

tion. The body portion of the hame comprises a rib 1, extending approximately the entire length of an integral flanged portion 2. The flanged portion 2 of the hame constitutes the base portion thereof. Said flanged portion is flat upon its inner face, and by reason thereof it provides a suitable surface which may engage a pad or collar positioned upon the animal. The rib 1 provides reinforcing means for the hame throughout its entire length. Owing to the peculiar construction of the body portion of the hame—to wit, the formation of a rib positioned upon the base portion thereof—the durability of the hame is greatly increased. Each end of the hame is provided with parallel integral extensions 4 4, as clearly depicted in Fig. 5, the parallel extensions constituting a bifurcated portion for each of the ends of the hame. A removable looped member 5 is secured within the upper bifurcated portion of the hame by any suitable means, as 6, and if it is desired a looped member 5 may also be positioned within the opposite or lower bifurcated end of the hame.

Formed intermediate the ends of the body portion of the hame are parallel integral lugs or ears 7 7, which project from said body portion at right angles to the flange 2. The parallel lugs or ears 7 7 constitute a bracket, which is employed for retaining a hook 8 upon the hame when said hook is secured by fastening means 9, preferably a bolt, between said lugs 7 7. The hook 8 comprises a body portion 10, which is provided with an aperture 11 for accommodating the fastening means 9. The hook 8 is provided with an angular extension 12, which is turned downward, so that when the hook is pivoted to and retained in its normal position, as depicted in Fig. 1, the downward extension 12 will be positioned comparatively near the upper surface of the upper lug 7. This peculiar structure of the hook is employed for the purpose of positively securing a trace in a connected condition with the hame. It will be obvious that if a trace is positioned upon hook 8 the portion of the trace which is interposed between the flanged portion 2 and the body portion 10 of the hook will be prevented from becoming disassembled from said hook, for the reason that it is securely fastened thereto, as the hook, when in its normal position, together with

the upper lug 7, constitutes substantially a solid link. If it is desired to remove the trace from off the hook, it may be accomplished by swinging the hook 8 around to the front, as illustrated in Fig. 3, and when the hook is in such position the extension 12 is removed from the body portion of the hame a considerable distance and provides a comparatively wide mouth. This peculiar construction of the hame produces fastening means for the trace, which is exceedingly simple in construction and of great utility. The flanged portion 2 is increased in thickness between the lugs or ears 7, 7, producing a reinforced or raised portion 13, which constitutes a rest for the hook. The formation of the rib or raised portion 13 between the lugs 7, 7 is accomplished by increasing the thickness of said flange toward its outer edge. The rib or raised portion 13 produces a socket or concaved portion, (illustrated in Fig. 3 by dotted line 14,) said socket 14 accommodating a portion of the hook 8. By reason of the rib or raised portion 13 many undesirable results involved in the employment of an ordinary hame are obviated, among which may be mentioned the chaffing of the animal, which is ordinarily done by the employment of a hame of the common type known to the patented art.

Each member of a pair of hames is connected at its upper end by fastening means 15, preferably a strap, which is secured to looped members 5, 5. The looped members 5, 5 and the fastening means when assembled lie in the same horizontal plane.

If it is desired, similar connecting means to that utilized for assembling the upper end of each hame of a pair may be also employed for connecting the lower end of each hame; but I prefer to employ a peculiarly-constructed fastening device for connecting the lower ends thereof.

The fastening device comprises a pair of pivotally-connected members 16 and 17. Member 17 is provided with an apertured portion 18, in which is positioned fastening means 19 when said fastening device is secured to one of the hames of the pair. The member 17 is provided with a hooked end, which is positioned within the bifurcated hooked end portion of the lever member 16 of the fastening device. The lever member 16 is provided with an angular end 20, which is adapted to partially surround the end of mem-

ber 17 which is secured to the hame, as seen in Fig. 1. Within the lower bifurcated portion of the other hame of the pair to that carrying the fastening device I preferably position one link of a chain 21 and secure said link within said bifurcated end by any suitable fastening means 22. When it is desired to draw together and retain the lower portion of the hames of a pair in a fixed position, member 16 of the fastening device is swung so as to position a link of the chain upon said member, and subsequently the member is swung forward upon its pivot, so as to place the same in approximately parallel position with the member 17, as illustrated in Fig. 1. It will be obvious that this member 16 performs the function of a lever for drawing the lower ends of the pair together.

Hames constructed in accordance with the present invention are preferably formed entirely of metal, and while my hame can be adapted for all the uses of an ordinary hame the same is preferably employed on animals used in mines, the hame being admirably adapted for such purposes.

While I have described in the foregoing description and illustrated in the accompanying drawings the preferred construction of my invention, it will be obvious to one versed in the art to which this invention relates that certain alterations, modifications, and changes may be made, and I therefore reserve the right to make such alterations, modifications, and changes as shall fairly fall within the spirit and scope of the present invention.

Having thus fully described my invention, what I claim as new, and desire to secure by Letters Patent, is—

1. A pair of hames each of which is provided at one of its ends with a bifurcated slotted portion, a link pivoted in each of said bifurcated portions, and means for connecting said links.

2. A pair of hames, each of which is provided at its ends with a bifurcated, slotted portion, and a link pivoted in each of the slotted portions, and means connecting said links.

In testimony whereof I affix my signature in presence of two witnesses.

MINER E. WORDEN.
